UNITED STATES PATENT OFFICE.

JOSEPH WALDEN, OF ORANGE, NEW JERSEY.

DESIGN FOR A WELT FOR SHOES.

SPECIFICATION forming part of Design No. 26,399, dated December 15, 1896.

Application filed November 25, 1895. Serial No. 570,117. Term of patent 14 years.

To all whom it may concern:

Be it known that I, JOSEPH WALDEN, a citizen of the United States, residing at Orange, in the county of Essex and State of New Jersey, have invented and produced a new and original Design for a Welt for Shoes, of which the following is a specification, reference being had to the accompanying drawing, in which Figure 1 is a perspective view of a welt showing my design and Fig. 2 is a cross-section.

The leading features of my design are the curved lines *a* and *b*, which bound the cres-

cent-shaped space shown in the drawing. The lines *b* and *c* are concentric. The base-line 1 5 is at right angles to the parallel lines 1 2 and 5 6, as also is the base-line 4 8 to the parallel lines 3 4 and 7 8. The line *a* is a line of compression of the welt material.

What I claim is—

The design for a shoe-welt, as herein shown and described.

JOSEPH WALDEN.
